US0D1026868S

(12) **United States Design Patent** (10) Patent No.: **US D1,026,868 S**
(45) Date of Patent: ** May 14, 2024

(54) **EARPHONE**

(71) Applicant: **YAMAHA CORPORATION**,
Hamamatsu (JP)

(72) Inventor: **Kazuki Kashiwase**, Hamamatsu (JP)

(73) Assignee: **YAMAHA CORPORATION**,
Hamamatsu (JP)

(**) Term: **15 Years**

(21) Appl. No.: **29/841,986**

(22) Filed: **Jun. 9, 2022**

(30) **Foreign Application Priority Data**

Dec. 14, 2021 (JP) ..... 2021-027485 D

(51) **LOC (14) Cl.** **14-01**

(52) **U.S. Cl.**

USPC **D14/223**

(57) **CLAIM**

The ornamental design for an earphone, as shown and described.

DESCRIPTION

FIG. 1 is a perspective view of an earphone showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the figures depict portions of the earphone that form no part of the claimed design.

1 Claim, 4 Drawing Sheets
